UNITED STATES PATENT OFFICE

FOSTER J. HULL, OF HAGERSTOWN, MARYLAND, ASSIGNOR TO PANGBORN CORPORATION, OF HAGERSTOWN, MARYLAND, A CORPORATION OF MARYLAND

SAND BLAST PRESSURE TANK

Application filed July 3, 1928. Serial No. 290,147.

In the operation of sand blast apparatus a considerable loss of efficiency as to the space occupied by the apparatus and the power expended in providing compressed air for the blast has resulted from the waste space in the pressure tank, from which the abrasive is fed to the mixing valve and hence to the hose which leads to the nozzle, or nozzles, from which the abrasive stream is projected against the work.

It will be understood that the tanks, in order to give the cheapest construction which will resist the pressures employed, are, in accordance with the existing practice, made cylindrical, the inlet valves for the abrasive being one at the center of each of the transverse or horizontal walls at the top and center, and the outlet to the mixing valve is formed in, or extends through, the cylindrical side wall at the bottom. The waste space referred to is partly due to the nature of the material handled, the abrasive ordinarily used having an angle of flow of about forty-five degrees, whereas the angle of flow of a liquid closely approaches zero, i. e., it varies but slightly from the horizontal. A further cause of waste space in the tank is due to the impossibility of projecting the material by gravity from the valve opening outwardly to the sides of the tank, without likewise deflecting its course downwardly. For this reason the outer portion of the tank entirely around the circumference at the top immediately below each horizontal partition is at no time filled with abrasive. This waste space is, as a matter of fact, due to the same cause, i. e., the angle of flow of the abrasive, otherwise, i. e., if it possessed the fluid properties of a liquid, the tank could be filled level to the top.

It will be noted, therefore, that the waste space is of two different kinds or classes, i. e., the unfilled waste space or dead air space around the circumference at the top, and the dead abrasive space at the bottom of each chamber. The latter is the space filled with abrasive which cannot be discharged through the outlet. The unfilled waste space, or dead air space, not only detracts from the efficiency of the apparatus

by necessitating a higher tank, as does the dead abrasive space, but it further detracts from the efficiency of the apparatus, as this unfilled space must be filled with compressed air after each refilling of the tank, which refilling operation, as will be easily understood, involves as a necessary step the discharge of the compressed air from the top chamber of the tank before the abrasive can be admitted from the outside.

In accordance with the previous practice, a tank having a capacity of abrasive discharge of two hundred and fifty cubic feet has a waste space capacity of six hundred fifty-four cubic feet. Such a tank, i. e., of such capacity, of eight feet in diameter, is eighteen feet high.

The object of the invention is to reduce the waste space and thereby increase the efficiency of the machine and reduce the size of the tank having a given predetermined discharge capacity. By the revision of the apparatus in accordance with the invention a tank of the same capacity, i. e., two hundred fifty cubic feet discharge, is reduced to a height of ten feet, the waste space being reduced from six hundred fifty-four to two hundred fifty-two cubic feet.

In the accompanying drawings I have illustrated a sand blast tank embodying the features of my invention in the preferred form.

In the drawings:

Figure 1 is a general view of the tank in the nature of a side elevation.

Figure 2 is a top plan view of the apparatus.

Figure 3 is a horizontal section on the line 3-3 of Figure 1, looking downwardly.

Figure 4 is a vertical section on the line 4-4 of Figure 2.

Figure 5 is a fragmentary view showing the compressed air supply and release connections and control for the upper chamber of the tank.

Figure 6 is a diagrammatic view in the nature of a central vertical section of the tank, indicating the waste spaces, consisting of dead air space and dead abrasive space.

Figure 7 is a top plan view of the same, also diagrammatic.

Figure 8 is a diagrammatic view showing the waste spaces, comprising dead air space and dead abrasive space, in accordance with the previous practice.

Figure 9 is a top plan view of the tank as shown in Figure 8.

Figure 10 is a diagrammatic view in the nature of a plan showing the manner of supplying air to the cylinder valves to operate the same.

Figure 11 is a diagrammatic view in the nature of a plan illustrating the manner of supplying air to the mixing chambers and to the lower chamber of the tank.

Referring to the drawings by numerals, each of which is used to indicate the same or similar parts in the different figures, the apparatus, as shown, comprises a sand blast pressure tank 1 divided into two chambers, referred to herein as the upper or primary chamber 2 and the lower or secondary chamber 3. The tank, in accordance with the regular practice, has an upwardly concave head 4 serving as the top wall of the upper chamber and an upwardly concave central partition 5 serving as the top wall of the lower chamber and the bottom wall of the upper chamber.

In accordance with the previous practice there was an abrasive admission valve in the center of the top wall 4 of the upper chamber. In the apparatus of the invention there is a series of such valves 9 arranged around the chamber and spaced away from the center. These valves cooperate with valve seats 6 surrounding the valve openings 7. It will be noted from Figure 6 that while the valves are spaced away from the center of the concavity they are not raised perceptibly above the lowest level of the top wall 4.

In accordance with the invention, the top wall 5 of the lower or supplementary chamber 3 is also provided with abrasive admission valve openings 17, likewise spaced away from the center and arranged along the periphery of the tank. These valve seats are closed by abrasive valves 19 cooperating with valve seats 16 and the valve and valve openings are, in the form of the invention shown, three in number.

The number of valve openings and valves used is immaterial in both instances, though the valves of the two series preferably correspond.

In accordance with the preferred form of invention the abrasive from the lower chamber is fed to the hose lines which, in turn, lead to the sand blast nozzles by way of mixing valves 70. As shown, there are two of these mixing valves corresponding to each of the abrasive feeding valves 9 and 19 respectively. While this arrangement is

found convenient, it is not essential to the invention. In the apparatus shown, there are three of the valves 9 for admitting abrasive to the upper chamber 2 and three of the valves 19 for admitting abrasive from the upper chamber 2 to the lower chamber 3, and there are six of the mixing valves 70 for mixing the abrasive with compressed air in accordance with the well known practice and feeding the mixture of abrasive and compressed air to the hose whereby it is fed to the nozzles. These six mixing valves are connected to the outer cylindrical wall of the tank 1 at the bottom by passages 72, Figure 6, the abrasive being caused to flow by gravity from the tank into the mixing valves, as best illustrated in Figure 6.

Figure 6 shows the position of rest of the dead abrasive when the supply of abrasive subject to discharge has been exhausted. In this figure the dead abrasive in the upper chamber is indicated by reference character 90, the area in the upper chamber from which the abrasive may be discharged by reference character 91 and the dead air space 92 in both chambers by reference character 93. The dead abrasive in the lower chamber is indicated by reference character 93. The area in the lower chamber from which the abrasive is discharged is indicated by reference character 94.

Figure 8 shows for the purposes of comparison a tank arranged in accordance with the previously existing practice, from which tank the available dischargeable abrasive has been discharged. In this figure the dead abrasive in the upper chamber is indicated by reference character 95, the dead air space in both chambers by reference character 96, and the area previously occupied by the abrasive, which has been discharged from the upper chamber, by reference character 97, and from the lower chamber, by reference character 98. The dead abrasive in the lower chamber is indicated by reference character 99. In this apparatus the abrasive filling valves are indicated by reference character 9' in the center of the upper partition 4' or top of the tank, and by 19' in the center of the partition 5', which separates the upper and lower chambers and the single mixing valve at the bottom of the lower chamber connected to the side wall thereof, is indicated by reference character 7'.

The principle of operation of this tank is similar to that described in my Patent No. 1,710,169. While the air pressure means is not a feature of the invention, otherwise than as to the arrangement already described whereby the waste space consisting of dead air space and dead abrasive space is reduced, the said air pressure means will be described so far as is necessary to a full comprehension of the drawings.

Air under pressure is led from any convenient source by way of an air pressure supply pipe 47, Figure 11, to upright air pressure pipes 25, Figure 2, which, in the machine shown, are three in number, one for each of the filling valves in either set of valves in either of the heads 4, 5, i. e., the valves 9 or 19, though the exact arrangement and number of pipes and valves is immaterial.

The upright pipes 25 are connected at the bottom by branch pipes 71, see Figure 1, to the respective mixing valves 70, there being in the form of machine shown two mixing valves for each of the upright pipes 25 and for each of the filling valves in each set.

Each upright pressure pipe 25 is also connected by a pipe 22 to the lower pressure chamber 3, the air being delivered in the form of machine shown by way of a cup 21 directly beneath the corresponding filling valve 19 which is operated by the air and may be assisted in its operation by a spring 20, the operation of the filling valves in this general way being well understood, and fully described in Patent to Foster J. Hull, No. 1,710,169.

Each of the upright air pressure pipes 25 is also connected to a cylinder valve 35, see Figure 4, by way of a pipe 49. This cylinder valve includes a double acting poppet valve 65 which is operated by a piston 60 to open and close alternately ports 63 and 66 respectively above and below the valve. The port 63 connects the passage 49 by way of valve passage 51 and the pipe 54 to the filler valve pipe 12, Figures 4 and 5, which operates the upper filler valve 9, it being understood that there is a cylinder valve 35 and passages as described for each of the respective filler valves 9. The pipe 12 opens beneath the valve through a cup 10 and operates the corresponding valve 9 in a well known manner, see above mentioned application of Foster J. Hull, also serving to supply air under pressure to fill the tank at the proper time in accordance with the practice.

Each pipe 54 contains a non-return valve or check valve 55, Figure 5, which opens toward the tank admitting air under pressure to the tank by way of the pipe 54 and 12 when the valve seat 63 is opened by the double valve 65 and when the valve seat 63 is closed and the exhaust seat 66 is open, the air is exhausted from the upper chamber 2 by way of the pipe 56 which is controlled by a check valve 57, it being understood that when the exhaust seat 66 is open to the exhaust passage 50 and the pressure seat 63 is closed, there is no tendency for pressure air from the chamber 2 to pass the check valve 55 and re-enter the tank as the pres-

sure in this direction is equalized. The air from the tank will, therefore, be freely exhausted by way of the pipe 56, check valve 57, downward through pipe 54 to exhaust seat 66 and the exhaust passage 50.

The mixer valves 70 are connected to the tank at the bottom by passages 72, being spaced around the periphery of the tank in any suitable manner as indicated in Figure 3. The abrasive is supplied by gravity to these mixer valves, air pressure being maintained in the tank in any suitable manner as by way of passage 22, and pressure air is further supplied to the mixer valves by way of the upright pipes 25 and branch pipes 71 supplying a stream of mixed abrasive and air under pressure, which can be conducted from each valve by way of a hose 73, Figure 1, to be directed against the work by means of a nozzle or the abrasive stream may be distributed from each mixing valve to several different nozzles.

In operation, each of the cylinder valves 35, one for each pipe 25, is controlled as to the position of the piston 60 and hence as to the position of the double poppet valve 65, effecting the opening and closing of the pressure seat 63 and the exhaust seat 66 by means of a supply of air under pressure led to the cylinders 35 by way of a small pipe 43, the supply of air to said pipes 43 being controlled in any suitable manner as by means of a three-way valve 41 which may be automatically, or otherwise operated, as preferred.

This valve controls and determines the supply of air to the pipe 43 from an air pressure supply pipe 80 which leads to the valve from a suitable source of air pressure supply and also controls the release of the air from the pipe 43 and from the cylinders by way of the exhaust or release pipe 81, also connected to the valve 41. The pressure in the pipe 80 may be higher than in pipe 47, but this is not necessary to the operation of the machine.

When the tank is in operation a quantity of abrasive is supplied to the head 4, the same being delivered thereto in any suitable manner. This is piled upon the head 4. To admit the abrasive to the upper chamber 2, which is in the nature of an air lock, the pressure in this chamber, which at the time of transfer is equal to working pressure in the lower chamber, must be released. To accomplish this the three-way valve 41 is turned to a position in which the pipe 43 is open to the exhaust 81. This relieves the pressure on the top of the piston 60, Figure 4, and permits it to raise in response to the air pressure beneath it, i. e., in the cylinder 35, it being understood that the operation described takes place in each of the cylinders 35 and in connection with each of the filling valves 9.

The upward motion of the piston 60 moves valve 65 upwardly closing the pressure seat 63 and opening the exhaust seat 66 to the exhaust pipe 50, which provides for release of the air from the tank by way of the pipes 56, see particularly Figures 7 and 5, through the check valve 57 and by way of the lower branch of the pipe 54, to the valve passage 51 where it passes to the exhaust pipe by way of the exhaust seat 66.

When the pressure in the chamber 2 has been sufficiently exhausted the filling valves 9 open in response to the pressure of the abrasive thereon and as much abrasive as can be admitted by gravity in this way is admitted to the upper chamber 2. In this connection it will be observed that the inflowing abrasive is excluded from, i. e., it cannot be supplied to the portions of the upper chamber indicated by shading 92 in Figure 6, and referred to as the dead air space.

When the upper chamber 2 has been filled as far as can be accomplished in this way, the valve 41 is turned and air is admitted from the supply 80 to the pipe 43, the exhaust 81 being closed. The downward pressure on the top of the pistons 60 thus established by admission of air from the pipe 43 assisted in the initial portion of the operation by the downward pressure on the top of the valve 65, which is closed against the pressure seat 63, moves the valve 65 downwardly, opening the pressure seat 63 and closing the exhaust seat 66.

Referring again to Figure 5, it will be understood that when the exhaust is closed and the pressure port 63 is opened, air under pressure will enter the chamber 2 of the tank, going from the valve passage 51 by way of the pipe 54 through the check valve 55, Figure 5, which it opens, and to the pipe 12 which enters the cup 10 beneath the valve 9, it being understood that there are three of the valves 9 and the operating means therefor in the apparatus shown.

It will be understood that at this time, the check valve 57 being closed by the air pressure in pipe 54, the entrance of the air to the tank by way of the pipe 56 is prevented. When the pressure in the upper chamber 2 has been sufficiently built up, it being understood that this chamber is now filled with abrasive, the pressure of the abrasive on the valves 19 in addition to the air pressure thus built up, serves to open the transfer valves 19 against the pressure of the spring 20 and the pressure of the air in the chamber 3, which is balanced by the pressure which has just been established in the chamber 2. The valves 19 being thus opened, the abrasive flows from the chamber 2 to the chamber 3, so far as the transfer can be effected by gravity. The condition in the chamber 2 being at the end of the

transfer operation, i. e., the operation of transferring the abrasive from the chamber 2 to the chamber 3, represented by the diagram, Figure 6, the dead abrasive in the upper chamber, i. e., that which cannot be transferred from the upper to the lower chamber being indicated by reference character 90 in the upper chamber.

When the transfer operation has been completed the controller valve 41 is again moved to the exhaust position, which causes the piston valve 60 to move upwardly, closing the pressure seat or port 63 and opening the exhaust seat 66 whereby the pressure in the upper chamber 2 is exhausted and it is refilled with abrasive. It will be understood that pressure is maintained at all times during the operation in the lower chamber 3 by way of the pipes 22 leading thereto from the upright air pressure pipes 25.

In accordance with the preferred embodiment of the invention, as illustrated, the nozzles, not shown, are supplied with mixed abrasive and air by way of the hose lines 73, one or more of which is connected to each of the mixing valves 70 of which, in the form of the invention shown, there are six, two mixing valves being supplied with pressure air from each of the air pressure pipes 25. These mixing valves 70 are distributed around the periphery of the tank with substantial uniformity, being connected to the sides of the tank at the bottom by way of pipes or passages 72. In this way the available volume of abrasive which can be removed from the lower chamber by way of the mixing valves is greatly increased as compared to the previously existing practice, the position of the dead or remaining abrasive being indicated at 93 in Figure 6, which shows the condition of the abrasive in the lower chamber when the available abrasive in that chamber has been exhausted. The abrasive is exhausted from area 94.

The corresponding condition, in accordance with the previously existing practice is illustrated in Figure 8, the dead abrasive in the lower chamber being indicated at 97 in said chamber.

It will be understood that the foregoing description of the operation relates to the supplying of abrasive by gravity to the upper chamber of the tank and to the transfer by gravity of the abrasive from the upper to the lower chamber, and to the feeding of abrasive by gravity to the mixing valves, from which it is propelled by the air under pressure supplied directly to the mixing valves from an outside source, being thus projected through the nozzle, by which it is directed against the work.

It will also be understood that the various features and details of the mechanism may be widely varied within the scope of the in-

vention and that any preferred means of handling the abrasive may be substituted for the gravity means as to part of the machine without affecting the operation of the other parts of the machine.

The main object of the invention is to equalize the distribution of the abrasive and increase the capacity of the tank by increasing, proportionately to the total volume of the tank, the volume to which the abrasive is supplied and from which it is removed as the tank is filled and discharged.

I have thus described specifically and in detail an air blast pressure tank apparatus embodying the features of my invention in the preferred form in order that the nature and manner of operating the same may be clearly understood, however, the specific terms herein are used descriptively rather than in a limiting sense, the scope of the invention being defined in the claims.

What I claim as new and desire to secure by Letters Patent is:

1. A sand blast apparatus comprising a tank having upper and lower chambers, means for supplying air under pressure to the upper chamber and releasing it therefrom, means for supplying air under pressure to the lower chamber, means for mixing air under pressure and abrasive connected to the lower chamber to receive abrasive therefrom, means for admitting abrasive to the upper chamber and a plurality of valves for transferring the abrasive from the upper chamber to the lower chamber by gravity, some of said valves being spaced outwardly from the center and spaced apart to equalize the distribution of abrasive as admitted to the lower chamber.

2. In a sand blast apparatus, a tank having an upper chamber and a lower chamber, transverse walls at the top of each said chamber, means for supplying air under pressure to the upper chamber and releasing air therefrom to relieve the pressure therein, means for supplying air to the lower chamber, air and abrasive mixing means connected to the lower chamber and means for supplying air to said mixing means, a plurality of valves in the top wall of the upper chamber admitting abrasive thereto by gravity, some of said valves being spaced outwardly from the center, said valves being spaced apart to equalize the distribution of abrasive in the upper chamber and means for transferring the abrasive from the upper chamber to the lower chamber.

3. In a sand blast apparatus, a tank having an upper chamber and a lower chamber, transverse walls at the top of each said chamber, means for supplying air under pressure to the upper chamber and releasing air therefrom to reduce the pressure therein, means for supplying air to the lower chamber, means for mixing air and abrasive con-

nected to the lower chamber and means for supplying air to said mixing means, a plurality of valves in the top wall of the upper chamber to admit abrasive thereto by gravity, some of said valves being spaced outwardly from the center and said valves being spaced apart to equalize the distribution of abrasive in the upper chamber and means for transferring the abrasive from the upper chamber to the lower chamber, by gravity, said means comprising a plurality of valves, some of which are spaced outwardly from the center, said valves being spaced apart to equalize the distribution of abrasive in the lower chamber.

4. In a sand blast apparatus, a tank having upper and lower chambers, means for supplying air under pressure to the upper chamber and to the lower chamber comprising a plurality of upright air pressure pipes, means for releasing air from the upper chamber, passages connecting each of said upright air pressure pipes to the upper and lower chambers, a plurality of mixing valves one said valve being connected to each of said upright pipes to supply air under pressure to the mixing valves, said mixing valves being connected to the lower chamber to be supplied with abrasive therefrom by gravity, said connections being spaced apart, an abrasive admission valve for each of said upright pipes controlled by the compressed air therefrom spaced apart and admitting abrasive by gravity to the upper chamber, a corresponding number of abrasive admission valves spaced apart and controlled by the compressed air admitting abrasive by gravity from the upper to the lower chamber and arranged around the lower chamber.

5. A sand blast apparatus comprising a container having upper and lower chambers, means for supplying air under pressure to the upper chamber and releasing it therefrom, means for supplying air under pressure to the lower chamber, a plurality of means for mixing air under pressure and abrasive and connections for said respective means to the lower chamber whereby the mixing means receive abrasive from said chamber, said connections being spaced apart, a plurality of valves for admitting abrasive to the upper chamber, and a plurality of valves for transferring the abrasive from the upper chamber to the lower chamber by gravity, both sets of abrasive valves being so spaced apart and distributed as to equalize the distribution of the abrasive into a series of piles over substantially the entire bottom surface of each chamber.

Signed by me at Brentwood, New York, this 18th day of June, 1928.

FOSTER J. HULL.
